UNITED STATES PATENT OFFICE.

CHARLES WESLEY DIXON, OF PITTSBURG, PENNSYLVANIA, ASSIGNOR OF ONE-HALF TO THOMAS PEACOCK, OF PITTSBURG, PENNSYLVANIA.

CEILING-BLOCK.

SPECIFICATION forming part of Letters Patent No. 699,914, dated May 13, 1902.

Application filed August 19, 1901. Serial No. 72,570. (No model.)

To all whom it may concern:

Be it known that I, CHARLES WESLEY DIXON, a citizen of the United States, residing at Pittsburg, in the county of Allegheny 5 and State of Pennsylvania, have invented a new and useful Ceiling-Block, of which the following is a specification.

This invention relates to ceiling-blocks and the like; and the object of the same is to provide a simple and effective device of this 10 class, insure perfect connection and contact, and facilitate the attaching and detaching of the devices and the insertion and renewal of the fusible connections.

15 The invention consists in the construction and arrangement of the several parts, which will be more fully hereinafter described and claimed.

In the drawings, Figure 1 is a perspective 20 view of a separated base-block and cap or cover embodying the features of the invention. Fig. 2 is a transverse vertical section of the two parts of the improved device shown assembled. Fig. 3 is a detail perspective view 25 of one of the members of the improved device. Fig. 4 is a transverse vertical section on the line 4-4, Fig. 1, showing the adjacent portion of the base-block in elevation.

Similar numerals of reference are employed 30 to indicate corresponding parts in the several views.

The numeral 1 designates the base-block, and 2 the cap or cover, the said parts being constructed similarly to the ordinary devices 35 of this class, the base-block having a cavity 3 for the removable reception of the cap or cover and to allow sufficient room for the terminals and fusible strips attached to the inner side or surface of the said cover, and at diamet- 40 rically opposite points of the rim of the block slots are formed to provide seats for the inwardly-extending right-angular extremities 4 of exteriorly-located contact-pieces 5, which are vertically disposed and in the form of 45 broad corrugated resilient hooks open at the bottom for the reception of the usual leads or main conductors 6. The inner ends of the extremities 4 have reversely-arranged down- 50 wardly-flared lips 7, adjacent to entrance- throats 8, leading to open spaces 9 between 55 said inner ends of the extremities and the

lower ends of non-conducting space-blocks 10, of the same material as the base-block and preferably forming an integral part of the latter, though said space-blocks may be made 55 separately and secured in place by any suitable means. The portions 11 of the side edges of the inner ends of the extremities 4 are turned up against the adjacent portions of the space-blocks to close the spaces 9 at said points, so 60 that the devices turned into the latter and carried by the cover will be limited in their movement and the full connection or assem- blage ascertained with accuracy. The base- block is also provided with screw-holes 12 for 65 the securement of the same to a ceiling, wall, or other support, and, as clearly shown by Fig. 2, said block also has vertical apertures 13, extending almost fully therethrough near the periphery for the insertion of securing- 70 screws 14 for the extremities 4 of the contact- pieces 5.

The cap or cover 2, like the base-block, is formed of some suitable insulating material and constructed with a central recess 15, from 75 which an opening 16 leads through the center for the passage of the terminals 17. Ad- jacent to the said recess 15 the cover is formed with a projecting flat ridge 18 to provide dia- metrically opposite segmental recesses 19, and 80 in seat-slots at diametrically opposite points in the ridge metallic contact-strips 20 are se- cured and have ends 21, extending over the recesses 19 for engagement with the spaces 9 between the extremities 4 of the contact-pieces 85 5 and the space-blocks 10 of the base-block to thereby conjunctively dispose the said ends 21 and extremities 4, the ends being turned into the spaces 9 through the throats 8. The recesses 19 are also defined and sepa- 90 rated by diametrically-arranged projections 22, on which are secured metallic contact- strips 23, having flat ends or extremities 24, to which the terminals 17 are connected. The strips 20 and 23 are formed of resilient ma- 95 terial, and the ends opposite the ends 21 and 24, respectively, thereof are rebent or turned over the bodies of said strips to provide yield- ing loops 25, which have upwardly-flaring ends 26 and depending side lips 27, located 100 over entrant edge slots 28 in the bodies of the strips beneath said loops. All of the strips

are of precisely the same construction, and one of the same is clearly shown by Fig. 3, and it is intended to use the said strips in devices other than ceiling-blocks where an accurate and positive contact is desired. Between the strips 20 and 23 are oppositely-extending fuse-wires 29, which may be in the form of narrow bands at times, though wires are preferred, the said wires being arranged between contiguous side edges of the strips and pass under the adjacent lips 27. When the cover is inserted in place in the base-block, the loops 25 are pressed toward the bodies of the strips forming a part thereof and the said lips move toward and into the slots 28 and firmly bind, at one side at least, against the said fuse-strips and insure a perfect contact and retention of the fuse-strips in place. This structure permits the fuse-strips to be easily inserted in the strips 20 and 23 without delay, so that replacement of said fuse-strips may be quickly carried on at any time in the event of a burn-out.

The improved device as an entirety is strong and durable, the parts are easily assembled, and also of a cheap nature. By making the strips 20 and 23 all of the same form a material reduction in the cost of manufacture results, and the parts will be more convenient in assemblage.

The resilient contact-pieces 5, having the exteriorly-located resilient hooks of corrugated form and open at the bottom, is also another advantageous feature of construction, as the main conductors can be readily placed in said hooks and held against disconnection by the corrugations which close the throats of the hooks. This form of contact-piece serves to as firmly hold the conductors as the clamps commonly employed without the disadvantages incident to the use of clamps and the delay in securing the same on the conductors.

Having thus described the invention, what is claimed as new is—

1. In an electric cut-out of the class set forth, the combination of a base-block having diametrically-disposed contact-pieces comprising inwardly-extending horizontal members and exteriorly-located vertically-disposed corrugated hooks open at the bottom, the inwardly-extending members forming seats with adjacent portions of the block, a cover having a series of contact-strips of similar form and comprising resilient loops with depending lips over portions of the bodies thereof beneath, fusible connections interposed between the loops and held by the lips and terminals attached to a portion of said strips, a part of the strips being arranged to engage the contact-pieces of the base-block.

2. In an electric cut-out of the class set forth, the combination with a base-block having contact devices or pieces which in part engage the main conductors, of a cover having a series of contact-strips of similar form and comprising resilient loops with depending lips over slots in the bodies thereof beneath, fusible connections interposed between the loops and held by the lips, and terminals attached to a portion of said strips, a part of the strips being arranged to engage the contact-pieces of the base-block.

3. A contact-strip for an electric cut-out having a loop bent to extending thereover and provided with depending lips at the sides which are located over side edge slots in the body of the strip below the loop.

In testimony that I claim the foregoing as my own I have hereto affixed my signature in the presence of two witnesses.

CHARLES WESLEY DIXON.
